RUBBER MILL

James T. Matsuoka, Brecksville, Ohio, assignor, by mesne assignments, to Stewart Bolling & Co., Inc., Cleveland, Ohio, a corporation of Ohio
Continuation-in-part of application Ser. No. 575,005, Aug. 25, 1966. This application Jan. 3, 1967, Ser. No. 606,942

4 Claims. (Cl. 18—2)

ABSTRACT OF THE DISCLOSURE

A mill, of the type commonly referred to as a rubber mill, for processing plastic material having a member extending across the operator's side of the mill and movably supported for interrupting the drive and stopping the mill upon movement of the member towards the mill as by the operator approaching the mill beyond a predetermined point.

This application is a continuation-in-part of my pending application, Ser. No. 575,005, filed Aug. 25, 1966, now abandoned.

In the operation of mills for processing plastic material of the type known as rubber mills, there is the possibility of serious injury to the operators in the event their hands and arms, etc., are drawn into the mill. Safety devices of various types have heretofore been proposed, for example, a member located above the mill which when grabbed and pulled by the operator stops the mill or a bar located in front of the mill and below the operator's knees which when pressed stops the mill, but these devices have met with only limited success.

The present invention provides a novel and improved plastic mill of the type referred to embodying safety features or devices which operate automatically to stop the mill in the event the operator approaches the mill beyond a predetermined position either intentionally or accidentally, and which preferably includes means which prevents the mill from being accidentally restarted.

Another object of the invention is the provision of a novel and improved safety device for attachment to or incorporation in a plastic processing mill of the character referred to which is simple and rugged in construction, reliable and automatic in operation and which will stop the mill in the event the operator either intentionally or accidentally approach the mill beyond a predetermined position.

A more specific effect of the invention is the provision of apparatus of the character referred to which will prevent accidental restarting of the mill after having been stopped by operation of the safety device.

The invention resides in certain constructions and arrangements of parts and further objects and advantages of the invention will be apparent from the following description of the preferred embodiment described with reference to the accompanying drawings forming a part of this specification in which similar reference characters designate corresponding parts, and in which:

FIG. 1 is a fragmentary front elevational view of a mill for processing plastic material embodying the present invention; and

2

FIG. 2 is a fragmentary sectional view approximately on the line 2—2 of FIG. 1.

Plastic processing mills of the character here involved and commonly referred to as rubber mills comprise two heavy metal rolls driven by suitable means usually an electric motor. The rolls are arranged horizontally with respect to one another with a slight space therebetween. The material to be processed is placed on the top of the rolls and is worked or processed by the action of the rolls which are rotated in appropriate direction and at appropriate speeds as is well understood in the art. The material being processed periodically requires some manipulation or handling by the operator with the result that his hands, etc., may be drawn into the mills, that is, between the rolls thereof.

The plastic processing mill shown in the drawing and designated generally by the reference character A is not herein shown or described in detail as it may be one of a number of such mills commercially available. Suffice it to say that the mill A comprises two processing rolls 10 and 11 rotatably supported in a suitable frame B comprising end members or housings 12 and 13. The mill A has incorporated in it the usual adjustments, etc., and is driven as by an electric motor, not shown, through a suitable speed reducer, etc.

The mill A includes safety apparatus designated generally as C for stopping the mill in the event the operator approaches the rolls either accidentally or intentionally beyond a predetermined position. The safety apparatus C shown comprises a bar 20 extending across the front of the roll 10 nearest to the operator's position and on a level with or slightly above the plane of the axes of rotation of the processing rolls 10 and 11. Opposite ends of the bar 20 are fixedly connected to and carried by the ends of a downwardly projecting, normally vertically-positioned arms 21 and 22 of bell crank levers 23 and 24 pivotally connected at their elbows or the apexes of the angle formed by their arms as by stud shafts 26 and 27 to opposite ends of housing members 12 and 13 of the mill frame B. The bell crank levers 23 and 24 are fixedly secured to reduced projecting ends of the stud shafts 26 and 27 by nuts 30 and 31, respectively, and the stud shafts 26 and 27 are supported for rotation about aligned axes in suitable brackets 32 and 33 bolted to the end frame members 12 and 13, respectively.

The other arms of the bell crank levers extend at right angles to the arms 21 and 22 and project toward the rolls of the mill. Only the arm 35 of the lever 23 clearly shows in the drawing, but the other lever has a similar normally horizontal arm. Angular movement of the bell crank levers is limited by stop pins 37 connected to the end housing 12 and 13 and extending horizontally therefrom through holes 39 in the horizontal arms of the bell crank levers. The holes 39 are slightly larger than the pins 37 thus permitting limited angular movement of the bell crank levers about the axes of the shafts or pins 26 and 27. In the embodiment shown the horizontal arm of the bell crank levers 23 and 24 are heavier than the vertical arms and the construction including the location of the pins 37 and the holes 39 are such that the bell crank levers engage and ride or rest upon the top sides of the stop pins 37. In other words, the location of the axes of rotation of the bell crank levers with respect to the center of gravity of the assembly comprising the

levers 23 and 24 and the bar 20 connected thereto is such that the assembly tends to rotate or is biased by gravity in a clockwise direction as viewed in FIG. 2. Alternatively the levers may be spring biased in the direction mentioned.

If the operator approaches the rolls of the mill either accidentally or intentionally beyond a predetermined point his body engages the bar 20 which in turn rotates the bell crank levers in a direction to move the horizontal arms thereof in an upwardly direction actuating two micro-switches 40 and 42 located thereabove and connected to the end housings 12 and 13 by brackets 44 and 46, respectively. The switches 40 and 42 are in series circuit with one another and when actuated operate electric circuits which disconnect and plug the drive motor for the mill in the event it is an alternating current motor. If the drive motor is a direct current motor, the motor may be dynamically braked. Alternatively, a mechanical brake may be applied upon the motor being disconnected or the drive for the mill may be through a disconnect clutch, in which event the switches could function to disconnect the clutch and apply a mechanical brake to quickly stop the mill.

Each of the switches 40 and 42 is provided with or incorporates a manual reset, designated generally as 44 and 46, respectively, making it necessary for the operator to reset both switches before the mill can be again started once they have been actuated by movement of the bar 20. This is an important feature of the invention as it incorporates or provides a built-in delay and prevents accidental restarting of the mill after being stopped. For example, as by the operator being thrown or pulled against one of the switches.

It is believed that it is obvious from the present disclosure that in the event the hand of an operator inadvertently or otherwise becomes entangled in the material being processed and the operator thereby pulled forward, that is, toward the rolls of the mill, he could almost instantaneously engage the bar 20 by his body, which bar is preferably about waist high, and the mill would be stopped before he would be seriously injured, if injured at all.

From the foregoing description of the preferred embodiment of the invention and alternative constructions, it is believed that it will be apparent that the objects heretofore enumerated and others have been accomplished and that there has been provided a novel and improved mill for processing plastic materials, and a novel and improved safety device for such mills.

While the preferred embodiment has been described in considerable detail the invention is not limited to the particular construction shown and referred to, it being understood that the invention may be embodied in other apparatus and it is the intention to hereby cover all adaptations and modifications thereof which come within the practice of those skilled in the art to which the invention relates and the scope of the appended claims.

Having thus described my invention, what I claim is:

1. In a mill for processing plastic material having a frame including spaced side housing in which a pair of processing rolls are supported for rotation about axes positioned generally horizontal with reference to one another, power actuated drive means for rotating said processing rolls, and means for quickly stopping rotation of the processing rolls upon interruption of said drive means, a pair of lever-like members pivotally connected to the adjacent side of said side housings on the operator side of said processing rolls, said lever-like members operating like bell crank levers having one of their arms extending downwardly in a generally vertical direction and the other of their arms extending in a general horizontal direction toward said processing rolls, a member extending between said lever-like members and connected thereto below their pivotal connections with said side housings, means limiting movement of said lever-like members

about their pivotal connections with said side housings, means biasing the assembly of said lever-like members and said member connected therebetween in the direction to move said member away from said processing rolls, and means actuated by movement of said assembly in a direction opposite to its biased direction for interrupting said drive means and quickly stopping rotation of said processing rolls.

2. In a mill for processing plastic material having a frame including spaced side housing in which a pair of processing rolls are supported for rotation about axes positioned generally horizontal with reference to one another, power actuated drive means for rotating said processing rolls, and means for quickly stopping rotation of the processing rolls upon interruption of said drive means, a pair of lever-like members pivotally connected to the adjacent side of said side housings on the operator side of said processing rolls, said lever-like members operating like bell crank levers having one of their arms extending downwardly in a generally vertical direction and the other of their arms extending in a general horizontal direction toward said processing rolls, a member extending between said lever-like members and connected thereto below their pivotal connections with said side housings, means limiting movement of said lever-like members about their pivotal connections with said side housings, means biasing the assembly of said lever-like members and said member connected therebetween in the direction to move said member away from said processing rolls, and electric switches having manual resets connected to said side housings for actuation by movement of said assembly in a direction opposite to its biased direction to interrupt said drive means and quickly stop rotation of said processing rolls.

3. In a mill for processing plastic material having a frame including spaced side housing in which a pair of processing rolls are supported for rotation about axes positioned generally horizontal with reference to one another, power actuated drive means for rotating said processing rolls, and means for quickly stopping rotation of the processing rolls upon interruption of said drive means, a pair of bell crank levers pivotally connected to the adjacent side of said side housings on the operator side of said processing rolls with one of their arms extending downwardly in a generally vertical direction and the other of their arms extending in a generally horizontal direction toward said processing rolls, a bar-like member extending between said bell crank levers and connected thereto adjacent to the lower ends of the downwardly extending arms thereof, means limiting movement of said bell crank levers about their pivotal connections with said side housings, means biasing the assembly of said bell crank levers and said bar-like member connected therebetween in the direction to move said member away from said processing rolls, and means actuated by movement of said assembly in a direction opposite to its biased direction for interrupting said drive means and quickly stopping rotation of said processing rolls.

4. Safety stop apparatus for a mill used to process plastic material and having a frame including spaced side housing in which a pair of processing rolls are supported for rotation about axes positioned generally horizontal with reference to one another, power actuated drive means for rotating said processing rolls, and means for quickly stopping rotation of the processing rolls upon interruption of said drive means, a pair of lever-like members adapted to be pivotally connected to the adjacent side of the side housings of the mill on the operator side of the processing rolls, said lever-like members being adapted to operate like bell crank levers with one of their arms extending downwardly in a generally vertical direction and the other of their arms extending in a general horizontal direction toward the processing rolls, a member extending between said lever-like members and connected thereto below their pivotal connections, means

limiting movement of said lever-like members about their pivotal connections, means biasing the assembly of said lever-like members and said member connected thereto between in a first direction to move said member away from the processing rolls, and means actuated by movement of said assembly in a direction opposite to said one direction for interrupting the drive means for the mill and quickly stopping rotation of the processing rolls.
